HAND DISPENSER FOR ADHESIVE TAPE

James H. Casey, Roseville, Minn., assignor to Minnesota Mining and Manufacturing Company, St. Paul, Minn., a corporation of Delaware

Filed Sept. 6, 1962, Ser. No. 71,578

Term of patent 14 years

(Cl. D74—1)

FIGURE 1 is a perspective view of a hand dispenser for adhesive tape, showing my new design;

FIGURE 2 is a side elevational view thereof;

FIGURE 3 is an end elevational view looking from the right of FIGURE 2;

FIGURE 4 is a side elevational view looking at the side opposite from that shown in FIGURE 2;

FIGURE 5 is an end elevational view looking from the left of FIGURE 2;

FIGURE 6 is a plan view looking from the top of FIGURE 2; and

FIGURE 7 is a plan view looking from the bottom of FIGURE 2.

I claim:

The ornamental design for a hand dispenser for adhesive tape, as shown.
